(57) **CLAIM**

The ornamental design for a tension leg platform, as shown and described.

DESCRIPTION

FIG. 1 is an isometric view of a tension leg platform in accordance with a first embodiment;

FIG. 2 is front elevation view of the tension leg platform of FIG. 1;

FIG. 3 is back elevation view of the tension leg platform of FIG. 1;

FIG. 4 is a top plan view of the tension leg platform of FIG. 1;

FIG. 5 is a bottom plan view of the tension leg platform of FIG. 1;

FIG. 6 is a left elevation view of the tension leg platform of FIG. 1;

FIG. 7 is a right elevation view of the tension leg platform of FIG. 1;

FIG. 8 is an isometric view of a tension leg platform in accordance with a second embodiment;

FIG. 9 is front elevation view of the tension leg platform of FIG. 8;

FIG. 10 is back elevation view of the tension leg platform of FIG. 8;

FIG. 11 is a top plan view of the tension leg platform of FIG. 8;

FIG. 12 is a bottom plan view of the tension leg platform of FIG. 8;

FIG. 13 is a left elevation view of the tension leg platform of FIG. 8; and,

FIG. 14 is a right elevation view of the tension leg platform of FIG. 8.

The broken lines are for illustrative purposes only and form no part of the claimed design.

1 Claim, 10 Drawing Sheets
